UNITED STATES PATENT OFFICE

BALDWIN H. KANNENBERG, OF OAK PARK, ILLINOIS, ASSIGNOR TO AMERICAN CAN COMPANY, OF NEW YORK, N. Y., A CORPORATION OF NEW JERSEY.

FRICITION-TOP CAN.

No. 863,721.

Specification of Letters Patent.

Patented Aug. 20, 1907.

Application filed March 11, 1907. Serial No. 381,692.

To all whom it may concern:

Be it known that I, BALDWIN H. KANNENBERG, a citizen of the United States, residing in Oak Park, in the county of Cook and State of Illinois, have invented 5 a new and useful Improvement in Friction-Top Cans, of which the following is a specification.

My invention relates to improvements in friction top cans. Its object is to provide a friction top can with a simple and efficient device for holding circulars, advertisements, directions samples or other articles within the recess or cavity of the dish shaped friction cover of the can.

It consists in providing the pry-off rim of the friction cover with one or more inwardly turned holding lips.

15 In the accompanying drawing forming a part of this specification, Figure 1 is a plan view of a friction top can embodying my invention. Fig. 2 is a central vertical section and Fig. 3 is a detail section of the cover.

In the drawing, A represents the body of the can, B 20 its annular top, C its bottom head and D the friction cover.

The annular top B has the customary depression b and annular depending friction seat wall b¹ surrounding the opening B¹ in the annular top B.

25 The friction cover D has the customary annular friction seat wall d tightly fitting and engaging the friction seat wall b¹ of the annular top B and an outwardly projecting pry-off rim d¹ reinforced by a downwardly and inwardly turned fold or flange d². The cover D is provided with inwardly projecting integral holding lips d³ preferably four in number for retaining circulars, sam-

ples advertisements, directions or other articles F within the cavity or recess D¹ of the friction cover D. These holding lips d³ are preferably formed by cutting or notching the pry-off rim of the friction cover as illustrated in the drawing, and turning or folding the same inwardly. 35

The externally projecting pry-off rim is thus made sectional or segmental, the portions thereof between the segments being turned inwardly over the cavity of the 40 cover and thus serving as holding lips to retain circulars or other articles within the recess of the cover.

I claim:—

1. In a friction top can having a depressed annular top and a friction cover furnished with an outwardly projecting integral segmental pry-off rim, and provided with inwardly projecting integral holding lips for retaining circulars, advertisements, directions or other articles within the cavity of the cover, substantially as specified. 45

2. A friction top can having a recessed cover provided with an integral outwardly projecting marginal segmental folded rim, and integral inwardly projecting and folded holding lips for retaining articles within the cavity of the cover, substantially as specified. 50

3. A can cover having an outwardly projecting segmental rim furnished with integral inwardly turned holding lips for retaining articles within the cover of the can, substantially as specified. 55

4. A recessed can cover having an outwardly projecting segmental rim and inwardly turned integral holding lips 60 for retaining articles in the cavity of the cover, substantially as specified.
